INFANT'S SLEEPING GARMENT

Vanda S. Peterson, Chicago, Ill.

Application July 17, 1948, Serial No. 39,361

1 Claim. (Cl. 128—134)

1

This invention relates to sleeping garments for infants and more particularly to pajama type garments having legs.

It is a primary object of the invention to provide a garment of this class with cords attached thereto for hitching the child's feet to members of the bed in which the infant sleeps.

It is an important object of the invention to provide a sleeping garment of this character, which serves as a means to restrict the infant's foot and leg movement sufficiently to prevent its kicking the covers off, and otherwise disarranging the covers; to prevent the infant from getting out of position; and to do this without undue restraint upon the infant's necessary normal movements.

It is a further object to provide an infant's pajama garment of this type with an independent set of cords at the foot end of each leg of the pajamas, which may both be conveniently and quickly tied to members of the entrance side of the bed.

It is also an object to provide a pajama garment of this class with feet enclosing sections, to the toe end of which the hitching cords are secured, so that the infant may turn without wrapping the cord about its legs to any serious extent.

It is also an object to provide such a garment for economical manufacture, and which is consistent with the conventional styles and manner of making same.

In the accompanying drawing of the invention, Figure 1 is a fragmentary plan view illustrating the preferred form of the invention, and

Figure 2 is a fragmentary outer side view of one of the pajama legs and shows the preferred manner of embodying the cords with same.

Similar characters of reference designate similar parts throughout the drawing.

Referring to Figure 1, the numeral 1 designates an ordinary infant's bed or crib having corner posts 2 and the usual vertical bars 3. The entrance side of the bed is provided with a conventional drop gate 4, through the way of which the infant is usually placed in bed, as well understood by those experienced in bedding children.

In this example of the invention the numeral 5 designates the lower portion of an infant's pajama type sleeping garment having legs 6 and 7 with respective foot inclosing sections 8 and 9. In this instance the infant is lying on its back, which is considered by many to be a preferred position.

2

Pairs of cords 10 and 11 are secured respectively to the extreme toe covering parts of the foot sections 8 and 9, said cords being conveniently provided from flat strands of braided material.

5 The pair of cords 11 are handily tied together somewhat loosely about the more adjacent corner post 2 and thus hitch the left foot and leg of the infant to said post, through the connection of said cords to the foot section 9. Said cords are not drawn sufficiently to cause any discomfort to the infant, but merely sufficient to restrict the movement of the respective foot and leg inwardly or upwardly within approximate limits. In the same manner the cords 10 are tied about one of 10 the vertical bars 3, the right boot of the child being restricted to a somewhat crossed over position on the left leg as rather exaggeratedly illustrated.

15 The bed covers (not shown) are tucked over the infant and it has been found by repeated trials that the infant can now turn and move generally with enough freedom for complete comfort and at the same time be sufficiently restrained to prevent disturbing the covers, while 20 without such restriction it usually kicks the covers off its legs and feet and by continued rolling and twisting often entirely removes the covers from its body.

25 The legs 6 and 7 are made with conventional seams 12 down the outer sides and the garment is otherwise so constructed as to continue these seams along the corresponding sides of the foot sections 8 and 9, so that in sewing the cords 10 and 11 to the toes of said foot sections said cords are likewise extended along over said seams throughout their length, from the juncture with 30 said sections, which feature adds to the stability and appearance of the garment.

35 From the foregoing it will be seen that the infant is very readily and satisfactorily placed in bed from the entrance side thereof, in a manner to avoid any worry about its remaining covered.

40 Button holes 13 are provided in the free ends of the cords 10 and 11 by which they may be engaged with the regular garment buttons 14, when not in use, it being understood that special buttons (not shown) may be provided for this purpose, as desired.

45 While in this example of the invention one of the preferred forms of construction has been illustrated and described, such construction is capable of variation and modification without departing from the spirit of the invention. I 50 therefore do not wish to restrict myself to the

precise details in the exact forms set forth, but desire to avail myself of such variation and modification as may come within the scope of the appended claim.

The invention claimed is:

In an infant's sleeping garment having legs with feet, each associated leg and foot having a longitudinal seam in common, a cord for each leg and foot serving as a hitch for engaging said garment to the frame work of the bed in which the infant sleeps, each of said cords extending along a longitudinal seam of the respective leg and foot and serving to cooperate therewith in the formation of said seam.
